UNITED STATES PATENT OFFICE

JOHN A. WATT, OF CLARKSBURG, WEST VIRGINIA, ASSIGNOR TO PITTSBURGH PLATE GLASS COMPANY, A CORPORATION OF PENNSYLVANIA

APPARATUS FOR DRAWING SHEET GLASS

Application filed April 4, 1928. Serial No. 267,209.

The invention relates to apparatus for drawing sheet glass. It has for its object the provision of means for preventing the sheet being drawn from thinning along lines inward from the side edges of the glass, but adjacent thereto, in the use of the Slingluff drawing process and apparatus, as disclosed in the Slingluff Patent No. 1,549,513. In the use of this apparatus, there is a tendency 5 of the sheet to thin as indicated at *a* in Fig. 4, which shows a horizontal section of the marginal portion of a sheet produced on the Slingluff machine. This thinning of the sheet tends to increase the percentage of the 15 breakage, and requires that a wider margin of the edge shall be trimmed off than would otherwise be the case. The present invention is designed to remedy this condition. One embodiment of the invention is illustrated in 20 the accompanying drawings, wherein:

Figure 1 is a vertical section on the line I—I of Fig. 2. Fig. 2 is a vertical section on the line II—II of Fig. 1. Fig. 3 is a plan view of the draw bar to which the invention particularly relates. And Fig. 4 is an enlarged horizontal section through the edge of a sheet produced on the Slingluff machine not employing the improvement to which the present invention relates.

Referring to the drawings, 1 is the end of a melting tank, preferably of the regenerator type; 2 is the forehearth or drawing tank communicating at its end with the melting tank; 3 is the lower end of the drawing apparatus provided with a series of rolls for drawing the sheet, such rolls being driven from the gears 4—4, 4—4, etc.; 5 is the glass sheet which is being drawn from the forehearth; and 6 is the draw bar to which the invention particularly relates. The draw bar is provided with the usual slot 7 extending from one end of the bar to the other and with a pair of projections 8, 8 at each end projecting upwardly toward the surface of the bath, as indicated in Fig. 2. These projections are located just beneath the marginal portions *a*, *a* of the sheet, which are normally drawn somewhat thin in the Slingluff operation, as heretofore referred to and as indicated in Fig. 4, 45 wherein the thin portions *a* are located about

5 inches from the extreme edges of the sheet. The projections 8, 8 increase the chilling or shielding effect of the draw bar beneath the marginal portions of the sheet and cause these edges to thicken up so that the breakage is reduced and the sheet may be trimmed closer to the edge than would otherwise be the case, thus increasing the production of the machine.

What I claim is:

1. The combination with a machine for drawing a glass sheet continuously from a bath of molten glass, of a draw bar of refractory material submerged in the glass beneath the line of generation of the sheet having projections located directly beneath the marginal portions of the sheet and beneath the surface of the glass a slight distance inward from the extreme outer edges thereof, and approaching nearer to the surface of the bath than does the portion of the draw bar intermediate said projections.

2. The combination with a machine for drawing a glass sheet continuously from a bath of molten glass, of a draw bar of refractory material submerged in the glass beneath the line of generation of the sheet and extending entirely across the bath with humps or shoulders located directly beneath the outer portions of the sheet a short distance inward from the extreme outer edges thereof, said humps approaching nearer to the surface of the bath than do the portions of the bar lying on both sides of the projections.

In testimony whereof, I have hereunto subscribed my name this 28 day of Feb., 1928.

JOHN A. WATT.
